Primary Examiner — Elizabeth Albert(74) *Attorney, Agent, or Firm* — Ohlant, Greeley, Ruggiero & Perle, L.P.(57) **CLAIM**

The ornamental design for a writing instrument cap, as shown and described.

DESCRIPTION

FIG. 1 is a perspective view of an ornamental design for a writing instrument cap according to the present invention; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof rotated 180 degrees from FIG. 6.

The broken lines in FIGS. 1 and 4 to 7 are included for the purpose of showing portions of the writing instrument cap that form no part of the claimed design.
